UNITED STATES PATENT OFFICE.

ALFRED A. BOECK, OF NEW YORK, N. Y.

DESIGN FOR A FABRIC FOR WINDOW-SHADES OR SIMILAR ARTICLES.

40,423.

Specification for Design.

Patented Dec. 28, 1909.

Application filed July 9, 1909. Serial No. 506,859. Term of patent 7 years.

To all whom it may concern:

Be it known that I, ALFRED A. BOECK, a subject of the Emperor of Germany, residing in the city of New York, borough of Manhattan, in the county and State of New York, have invented a new, original, and ornamental Design for a Fabric for Window-Shades or Similar Articles, of which the following is a specification, reference being had to the accompanying drawing, forming a part thereof.

The figure is a fragmentary view of a fabric for window shades or similar articles, illustrating my new design.

I claim:

The ornamental design for a fabric for window shades, as shown.

ALFRED A. BOECK.
